WINDOW OPERATING MECHANISM

Filed April 8 1922

2 Sheets-Sheet 2

UNITED STATES PATENT OFFICE.

HERMAN C. BUJACK, OF CHICAGO, ILLINOIS.

WINDOW-OPERATING MECHANISM.

Application filed April 8, 1922. Serial No. 550,624.

To all whom it may concern:

Be it known that I, HERMAN C. BUJACK, citizen of the United States, residing at Chicago, county of Cook, State of Illinois, have 5 invented a certain new and useful Improvement in Window-Operating Mechanism, and declare the following to be a full, clear, and exact description of the same, such as will enable others skilled in the art to which 10 it pertains to make and use the same, reference being had to the accompanying drawings, which form a part of this specification.

My invention relates to improvements in window-operating mechanism.

15 The object is to provide window-operating mechanism of such a character that the upper and lower sliding sashes of a window may either be moved simultaneously or independently without the use of weights, 20 pulley cords, or the like and which mechanism is so constructed that either or both windows may be locked at any position to which they may be moved, so as to prevent their movement in any other manner than 25 with the prescribed operating mechanism.

A further object is to provide in connection with lift windows so operating, simple, effective, automatic means for locking the windows against a movement except 30 through the use of my operating mechanism at any position to which the windows may be moved merely by disconnecting the operating mechanism.

My invention does not require for installation 35 the use of a frame pocket and it may be fitted to any sliding window provided with a parting stop and is positioned well concealed between the meeting rails of the upper and lower sashes.

40 These and other objects, together with details of construction will more fully appear in the following description, appended claims and accompanying drawings, in which:

45 Figure 1 is a horizontal sectional view, partly broken away, showing my operating mechanism in place.

Fig. 2 is an end elevation of the operating mechanism taken on the line 2-2 of 50 Fig. 1.

Fig. 3 is a perspective, partly broken away, of the locking member.

Fig. 4 is a perspective of the locking member casing.

Fig. 5 is a fragmentary view showing the 55 meeting rails of upper and lower sashes in vertical cross-section.

Fig. 6 is a fragmentary elevation of a portion of the lower sash.

Fig. 7 is a fragmentary perspective of a 60 portion of the pivoted rack bar.

Fig. 8 is a cross-sectional view through my removable inner stop at its point of attachment to the jamb.

Fig. 9 is a perspective of a portion of the 65 securing means for my removable inner stop.

In the preferred construction shown in the drawing, the upper sash is indicated as 10; the side rails thereof as 10^a and the meeting rail as 10^b, while the lower sash is 70 indicated as 11, its side rails as 11^a and the meeting rail as 11^b. The upper and lower sashes are mounted in a window frame for sliding movement, the opposed jamb members of the frame being indicated as 12, the 75 outer stops as 13, the parting stops as 14, and the inner stops as 15.

I omit the weights and pulley cords usually found in this type of window construction and provide operating mechanism comprising a rotatably supported drive shaft 80 16 extending transversely the window frame between the meeting rails of the upper and lower sashes on a line with the parting stops 14. This shaft has a bearing at each end 85 in a plate 17 which plate is suitably attached to the window jamb 12 and mounted on the shaft at each end to rotate therewith. Adjacent the outer face of each plate 17 is a rack pinion 18. These pinions engage rack bars 19 secured to the side rails 10^a of the upper sash. The rack bars extend longitudinally the side rails and lie in the plane of the sash and are turned over the edge of the side rails as hereinafter described.

Similarly secured to the side rails of the lower sash are rack bars 20. However, in order that the upper sash may be operated independently of the lower sash, the rack 100 bars 20 secured to the side rails 11^a of the lower sash are provided at their upper ends with pivoted extensions 21 which project above the meeting rail 11^b, as shown in Figs. 6 and 7, so as to permit movement of this 105 pivoted section 21 in a plane parallel the plane of the sash and out of engagement with the rack pinion 18, thereby permitting

independent operation of the upper sash, while the lower sash remains in the closed relation.

On one end of the shaft 16 is mounted a gear 22 which gear is engaged with a main driving gear 23 which gear 23 is supported within a casing carried by the plate 17. This casing is formed from a U member 24, shaped as shown in Fig. 4. Secured to the side 24^a of this U-piece 24 is a member 25 to form the box which encloses the gear 23 and to the other side 24^b of this U-piece is slidably secured the member 26, which member 26 is provided with projecting ears 27, which ears engage in the teeth of the gear 22 to prevent rotation thereof. The centrally-disposed ear is turned over as at 28 and provided with a head 29 which engages in a slot 30 in the side portion 24^b. At the other end member 26 is provided with a turned-over arm 31 having a head 32 which engages in a slot 33 likewise formed in the side portion 24^b. This form of attachment of the member 26 to the side portion 24^b permits a limited guided movement of the member 26 relative the side portion 24^b and in a direction longitudinally the shaft 16, or so as to be moved in and out of the locked relationship with the gear 22. A spring 34 is provided which exerts a constant yielding tension tending to hold the locking member 26 inwardly toward the gear 22. This member 26 is provided with an opening 38 adapted to receive the end of the removable hand crank 35. The crank 35 has a loose fit in a bearing 36 which bearing is attached to the window casing 37. The crank is so shaped at the working end, here shown as being squared, as to pick up the gear 23 which is similarly formed, so that this gear 23 will rotate with the crank. Because of the loose fit of the crank in the bearing, the crank is movable to enter the opening 38 in member 26, though such opening is out of alignment with the opening through the fixed bearing 36 and the opening for the crank through the side portion 24^b. The normal position of the locking member 26, when under the influence of the spring 34, is such that the opening 38 through this locking member is out of alignment with the openings above mentioned. The crank forms a sliding engagement with the side wall of member 26, through the opening 38 so that when it is inserted through the opening 38 the member 26 is retracted against the tension of spring 34 sufficiently for the end of the crank to find a bearing in the opening 39 in the side portion 24^b of member 24. The crank holds the member 26 out of engagement with the gear 22, thereby releasing such gear and the shaft 16 to rotation to permit operation of the upper and lower window sashes. Rota-

tion of the crank drives the shaft 16 through the medium of gears 28 and 22 which are constantly in engagement with each other. When the crank is rotated the upper sash will be lowered and the lower sash lifted. However, if it is desired merely to operate the upper sash, the pivoted sections 21 of the rack bars 20 may be moved to one side out of engagement with the rack pinions 18 permitting independent operation of the upper sash.

Projecting laterally from the plates 17 into the path of the sliding sashes are pins 46 upon which are mounted rotary bearings 47 which travel in provided guideways 48 formed on the sliding face of the sashes. The rack bar 19 of the upper sash and 20 of the lower sash is turned over the edge of the side rail of each sash and forms a bearing engagement with these rollers. The guideway itself in which the rollers travel may be lined with a metal sheath 49, if desired.

In order to permit access to the lower sash for removal thereof, I have provided an improved type of stop and securing means. The jamb is recessed as at 40 and seated therein is a plate 41 slotted as at 42 and provided with beveled faces 43 on each side of the slot. A securing pin 44 provided with a transverse head 45 extends through an opening in the stop member 15 into the recess 40 and may be rotated so that the head 45 engages the sloping portions 43 of the plate drawing the entire stop inwardly into close fitting engagement with the jamb. It is apparent that the pin may be rotated so as to be completely removed from its engagement with the jamb. The outer bearing plate 46 may be secured to the inner stop to prevent defacing the stop through the operation of the pin.

What I claim is:

1. The combination in window operating mechanism, of a window frame fitted with upper and lower sliding sashes, a rotatable drive shaft extending transversely the frame between the meeting rails of said sashes and provided with a rack pinion at each end, adjacent faces of the side rails of said sashes provided with rack bars extending longitudinally said side rails and being in the plane of the sash and in engagement with the rack pinions of the drive shaft, each rack bar carried by the lower sash provided with a pivoted end extension which extends above the meeting rail of said sash and is adapted to be swung about its pivot through a plane parallel the plane of the sash and out of engagement with the corresponding rack pinion of the drive shaft, means adapted to be coupled with said drive shaft to rotate the same, and means for automatically locking the said drive shaft against rotation coincident with

the uncoupling of the mechanism adapted to rotate the drive shaft.

2. In window operating mechanism, a window frame, an upper and a lower sash mounted within the frame for slidable movement, rack bars carried on adjacent faces of the side rails of said sashes, a rotatably supported drive shaft transversely the window frame between the meeting rails of said sashes provided with pinions engaging said rack bars to raise and lower the

sashes upon rotation of the shaft, the rack bars on one of said sashes formed in two sections, one section rigid with the sash, the other section pivoted thereto to be swung out of the path of engagement with the pinion carried by the drive shaft to permit independent operation of one sash only. 15

In testimony whereof, I sign this specification. 20

HERMAN C. BUJACK.
